BUFF CONSTRUCTION

Lester W. Kreilick and Herbert R. Taylor,
Fremont, Ohio

Application September 15, 1937, Serial No. 163,932

2 Claims. (Cl. 51—193)

This invention relates to buffing wheel elements and their assembly.

This invention has utility when incorporated in disks of woven fabric, stitch assembled, especially for combined utilities over widened ranges in grinding, or hard wheel operations, burnishing and polishing, or so-called loose buff operations.

Referring to the drawing:

10 Fig. 1 is a side view of a buffing section having an annularly complete stitched or hard portion and a central loose buff portion;

15 Fig. 2 is a side view of a buffing section having the stitched or hard portion annularly incomplete, being quartered by intersecting direction loose or vent strips;

20 Fig. 3 is a side view of a buffing section having the stitched or hard portion annularly incomplete, quartered by loose or vent strips outward from a central loose buff portion;

25 Fig. 4 is a side view of a buffing section of the general type of Fig. 2, with transverse ports to supplement ventilation at the strips radially outward;

30 Fig. 5 is a fragmentary view of a buffing section of the general type of Fig. 3, with ventilation promotion ports near the junction of the loose buff with the radial strips; and

35 Fig. 6 is a fragmentary diagrammatic showing 30 of the buffing sections assembled as a wheel on a buffing jack, with bladed ventilation means between the sections.

Warp and woof fabric disks 1 have the successive plies angularly offset (Fig. 5) as stitch assembled into a section. Criss-cross buff compacting stitching 2, (Fig. 1) provides an annularly complete hard buff section having successively opening pockets 3, 4, 5, as the disk is worn to decreasing diameter in operation. The practice for wear down of a hard buff initially of say 12" to 16" diameter when reduced to say 8" diameter, is not generally usable for further diameter reduction.

A factor of importance in the disclosure herein 45 is retention of value for the 8" diameter buff as brought to such dimension reduction by wearing down in use. By leaving unstitched region 6 radially inward as a minor disk area there results a loose buff cushioning center providing a resilient support for the working portion. This loose buff applicants have found serviceable down to 3" diameter, thereby saving from scrap or waste a useful range for 5" diameter reduction. Central assembly stitching 7 may retain the sections 50 in the peripherally loose grouping. Reducing the

stitched area, with requirement of less thread, has contributed a material percentage of polishing cloth for value in the polishing or loose buff range of operations.

5 Hard stitching 8, say as criss-cross (Fig. 2), is a working zone and may be of approximately full radial extent to the stitching 7, but herein quartered against annular continuity by unstitched strips 9 as loose buff radially extending channel portions, softening the cushioning section unit 10 against peripheral rigidity. The unstitched strip 9, besides its looseness attribute, has vent properties incidental thereto, a factor against excessive temperature rise in buffing operations.

15 Central loose buff portion 10 (Fig. 3) has radially therefrom unstitched strips 11, separating criss-cross stitched portions 12, isolated from the soft or loose portion 10, by arc stitching 13. The ventilation advantage in the dual form buff is 20 here present.

25 Ports or openings 14 (Fig. 4) directly through a buffing section are effective to supplement ventilation effectiveness of the unstitched radial strips 9. These ports are preferably located sufficiently inward as not to be disturbed in the function of the buffing wheel as a hard buff.

30 Ports 15 (Fig. 5) in the dual purpose buffing section, may be located at the region of demarcation hard to loose buff, and thereby not in practice interfere with the full peripheral use of the 35 hard buff to the loose buff diameter and direct use of the loose buff therefrom.

35 The respective sections have central hub openings 16 through which may extend shaft 16 mounted in bearing 19 and extending therethrough to carry pulley 20 driven by belt 21 in operating the buffing jack. The buffing wheel comprises a plurality of sections 21 having ports 15 of the respective sections in register. The sections 21 are spaced by blades 22 on spacer means 40 between the sections 21. Hub disks 23, 24, are in such compressing assembly for the sections 21 effected by the nut 25, that the peripheral portions of the sections overhang the blade into 45 wheel peripheral completeness.

45 Buff life increase, buff operation effectiveness in the varied different ranges for performance, have these values further supplemented by the ventilation properties incidental to the build-up 50 of the wheel as herein set forth.

The loose buff center in practice may act to distend centrifugally and serve to cushion the hard buff into the work as a further function of efficiency.

What is claimed and it is desired to secure by United States Letters Patent is:

1. A buffing wheel comprising a plurality of disks of woven fabric united to form a unitary structure, a plurality of rows of stitching applied to an outer annular working portion to compact and strengthen said working portion, an inner portion between the centre of the disks and the annular working portion being unstitched and loose in nature and of such an extent as to form a resilient support for the working portion.
2. A cushioned and ventilated buff comprising, a plurality of woven fabric disks united to form a

unitary structure, a plurality of rows of compacting stitching applied to an outer annular working zone in groups in the form of annular sectors which are spaced apart by unstitched channels connecting to an unstitched central portion of considerable extent, the unstitched central portion being loose in nature and forming a resilient cushioning support for the working zone and the unstitched channels extending from the unstitched central portion to the periphery 10 affording ventilating channels.
